DESIGN FOR A COMBINATION DESK UNIT OR SIMILAR ARTICLE

Corrado Marcantonio, New York, N. Y.

Application January 13, 1940, Serial No. 89,443

Term of patent 7 years

To all whom it may concern:

Be it known that I, Corrado Marcantonio, a citizen of Italy, residing at New York city, in the county of Queens and State of New York, have invented a new, original, and ornamental Design for a Combination Desk Unit or Similar Article, of which the following is a specification, reference being had to the accompanying drawing, forming part thereof.

Fig. 1 is a front perspective view of a combination desk unit or similar article, showing my new design.

Fig. 2 is a side elevation thereof on a reduced scale as viewed from the left of Fig. 1.

I claim:

The ornamental design for a combination desk unit or similar article, substantially as shown.

CORRADO MARCANTONIO.
